DRIER

Walter L. Kauffman, 2d, Erie, Pa., assignor to
 Lovell Manufacturing Company, Erie, Pa., a
 corporation of Pennsylvania

Application November 6, 1931, Serial No. 573,426
 Renewed February 29, 1936

4 Claims. (Cl. 100—50)

This invention is particularly designed for drying clothes and as exemplified is shown in connection with a drier in which the clothes are placed in a flexible bag and subjected to a squeezing action through the operation of a fluid on the bag, the extruded moisture being discharged from the clothes under pressure through the outlet, ordinarily through the cover. The present invention is designed to improve the manner 0 of securing and adjusting the cover with relation to the receptacle so as to facilitate the insertion and removal of the clothes and for directing the discharge of water from the receptacle. Features and details of the invention will 5 appear from the specification and claims.

A preferred embodiment of the invention is illustrated in the accompanying drawings as follows:—

Fig. 1 shows a central vertical section through the drier.

Fig. 2 a plan view of the drier.

Fig. 3 a view of the under-side of the cover.

Fig. 4 a section on the line 4—4 in Fig. 2.

Fig. 5 a section on the line 5—5 in Fig. 3.

10 1 marks the receptacle. It has a beaded edge 2 around its opening and a gasket seating groove 3 adjacent to the edge. A means of supplying fluid, usually water, to the receptacle is indicated at 4.

15 A flexible bag 5 has a sealing rib 6 around its upper edge adapted to seat in the groove 3.

The cover 7 has a tapered exterior edge 8 which engages the rib 6 forming an initial seal as the cover is put into place, the bead being definitely sealed by the pressure of the liquid as it is admitted to the receptacle. The cover is provided with a perforated straining plate 9 and this leads to a discharge passage 10 from which leads a 20 spout 11 extending from the side of the cover and away from the side of the receptacle.

25 The cover is provided with a series of radial projections 12 arranged just above the edge of the receptacle.

30 A locking ring 13 is of channel form, the lower flange extending under the beaded edge 2 and the upper flange being slotted forming projections 14 corresponding to the projections 12. The projections 14 and the projections 12 and the slots between them are so related to each other to form a bayonet joint permitting the assembly of the cover by a downward movement of the cover carrying the projections on the cover between the 35 projections on the ring and locking the cover in place by turning it circumferentially to bring the projections 12 under and into register with the

projections 14 in the manner of an ordinary bayonet joint.

The cover is hinged on the ring and is preferably provided with two hinge pintles 15, these hinge pintles being secured to lugs 16 extending from the ring. The pintles are approximately tangent to the circle of the cover and the hinge butts 17 are pivotally mounted on the pinte, these butts having preferably flaring openings so that they may move in a circular direction on the 10 pintles. The pintles are of sufficient length to permit the assembly of the projections on the cover through the slots between the projections 14 and then a turning of the cover through the freedom of the lugs 16 on the pintles 15 so as to 15 bring the cover into locked position.

The locking ring is preferably split having a pivotal connection through a bolt 18 at the hinge and a securing screw 19 at the point of separation opposite the hinge.

20

I prefer to arrange the spout directly opposite the hinge so that the spout may form a ready handle for lifting the cover. The spout also provides a handle by means of which the cover may be turned into locked position, or may be turned 25 to unlock the cover.

What I claim as new is:—

1. In a drier, the combination of a receptacle having an opening; means in the receptacle for extruding moisture from material to be dried; a 30 ring rotatably secured to the opening edge of the receptacle; a cover having a discharge passage leading from the receptacle and discharging above the ring, said cover and ring having a bayonet joint connection, the discharge passage being rotatively adjustable through the rotation of the ring; and a hinge between the cover and ring having hinge members axially movable to the axis of the hinge in the general line of the periphery of the cover and ring, the axial freedom of 35 the hinge permitting the assembly and release of the bayonet connection.

35

2. In a drier, the combination of a receptacle having an opening; means in the receptacle for extruding moisture from material to be dried; a 40 ring rotatively secured to the opening edge of the receptacle; a cover having a discharge passage leading from the receptacle over the ring; a hinge connection between the ring and cover; and a spout on said cover leading from the passage and 45 extending radially from the side thereof opposite the hinge.

40

3. In a drier, the combination of a receptacle having an opening; means in the receptacle for extruding moisture from the material to be 50

50

55

dried; a ring rotatively secured to the opening edge of the receptacle; and a cover secured to the ring and closing said receptacle, said cover having a discharge passage rotatably adjustable through the rotation of the ring.

5. In a drier, the combination of a receptacle having an opening; means in the receptacle for extruding moisture from the material to be dried;

a ring rotatively secured to the opening edge of the receptacle; and a cover secured to the ring and closing said receptacle, said cover having a discharge passage rotatably adjustable through the rotation of the ring, said cover and ring having a bayonet joint connection.

WALTER L. KAUFFMAN, II.
